NEEDLE WITH OPENABLE EYE

Lattrell Graham, Amarillo, Tex.

Application February 1, 1952, Serial No. 269,497

3 Claims. (Cl. 223—102)

1

This invention relates to thread needles and more particularly to a needle having an eye which can be opened for the insertion of a thread therein and closed to retain the thread in the eye, the needle being especially adapted for use with yarns of large size such as are used in making rugs.

It is among the objects of the invention to provide an improved needle which is particularly arranged for easy threading and especially adapted for use with large size yarns; which has an eye structure one side of which can be opened to permit insertion of a thread or yarn directly into the eye and reclosed to retain the thread or yarn therein; which has an eye formation provided in two parts, one of which is pivotally connected to the needle and which snap together in eye closing relationship and are easy to manually separate when desired; which has a portion of maximum diameter intermediate its length to provide enlarged holes in fabric for the passage of thread or yarn therethrough; which is entirely smooth and has no projections to catch in fabric through which the needle is passed; and which is simple and durable in construction, economical to manufacture, easy to use, and neat and attractive in appearance.

Other objects and advantages will become apparent from a consideration of the following description and the appended claims in conjunction with the accompanying drawing, wherein:

Figure 1 is a side elevational view of a needle illustrative of the invention with the eye of the needle shown in closed condition;

Figure 2 is a side elevational view similar to Figure 1 but with the eye of the needle shown in open condition; and

Figure 3 is a side elevational view of the needle when rotated approximately 90° from the position illustrated in Figures 1 and 2.

With continued reference to the drawing, the needle comprises an elongated body 10 formed of suitable material, such as steel, having intermediate its length a portion 11 of maximum diameter disposed somewhat nearer one end of the body than the other. The body tapers to a point 12 at its end furthest from the portion 11 of maximum diameter and has an eye formation, generally indicated at 13, at the side of the portion 11 remote from the point 12.

The eye formation 13 comprises a flattened leg 14 which extends from the body substantially at the portion 11 of maximum diameter along and substantially parallel to the longitudinal center line of the body, this leg being spaced to

2

one side of the longitudinal center line. The leg 14 is integral with the remainder of the body 10 and has its outer surface flush with the corresponding surface of the body, the leg being formed by cutting away one side of the body from the portion 11 to the nearest end of the body and the inner surface of the leg is substantially flat while the outer surface is transversely convex. At its distal end the leg 14 is provided with a projection 15 which extends substantially perpendicularly from the distal end of the leg 14 across the longitudinal center line of the body and is longitudinally curved so that it has a convex outer surface and a concave inner surface facing the portion of the body 10 at the proximal end of the leg 14.

The eye also includes a second leg 16 of substantially the same size and shape as the leg 14 and pivotally connected at one end to the body 10 at the body portion 11 of maximum diameter. The leg 16 is flattened, having a substantially flat inner surface facing the leg 14 and a transversely convex outer surface and is provided at its free or distal end with a projection 17 which extends perpendicularly from the distal end of the leg 16 toward the leg 14 and is longitudinally curved so that its outer surface is somewhat convex and its inner surface somewhat concave.

The body 10 is provided in the portion 11 thereof with a recess 18 which opens to the side of the body diametrically opposite the proximal end of the leg 14 and the leg 16 is provided on its end pivotally connected to the body 10 with a tongue 19 of partly cylindrical shape having a width substantially equal to the width of the recess 18 and provided with a transversely extending aperture. The body 10 is provided with apertures at the respectively opposite sides of the recess 18 which register with the aperture 40 in the tongue 19 and a pivot pin 20 extends through the registering apertures in the body 10 and the tongue 19 and pivotally connects the leg 16 to the body. The pivotal connection between the leg 16 and the body 10 is such that the leg 16 can swing away from the leg 14 a predetermined amount only, a maximum angle of approximately 50° between the legs 14 and 16 having been found to provide entirely satisfactory results in use.

When the leg 16 is swung toward the leg 14 to close the eye formation 13 of the needle the extension 17 on the distal end of the leg 16 constitutes a cap which snaps over the convex outer surface of the extension 15 on the distal end of the leg 13 so that the two legs are snapped to-

gether and resiliently held in eye closing relationship in which they are spaced apart and substantially parallel, as is particularly illustrated in Figure 1. The leg 16 can be swung away from the leg 14 to open the eye by grasping the body 10 in the fingers and applying finger pressure to the projection or cap 17 in the proper direction.

The eye formation 13 of the needle is easy to open and close and the needle has been found to have particular utility in the manufacturing of certain types of rugs wherein it is necessary to unthread and thread the needle at frequent intervals to work yarns of different colors through the fabric backing to provide desired patterns in the pile of the rug.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A needle comprising an elongated body of circular cross sectional shape tapered from a location intermediate its length to both its ends, said body being tapered to a point at one end and having at its other end an eye formation including a flattened first leg extending along and spaced to one side of the longitudinal center line of said body and provided at its distal end with a projection extending substantially perpendicularly therefrom through the longitudinal center line of said body, and a flattened second leg pivotally connected at one end to said body at a location substantially diametrically opposite the proximal end of said first leg and having on its other end a projection extending substantially perpendicularly therefrom toward said first leg and underlying the projection on said first leg to releasably hold said legs in spaced apart and substantially parallel relationship to each other with the eye of the needle therebetween when said eye formation is closed, said second leg being swingable away from said first leg to open said eye formation for the passage of a thread into said eye between the distal ends of said legs and swingable toward said first leg to close said eye at the distal ends of said legs.

2. A needle comprising an elongated body of circular cross sectional shape tapered from a location intermediate its length to both its ends, said body being tapered to a point at one end and having at its other end an eye formation including a flattened first leg extending along and spaced to one side of the longitudinal center line of said body and provided at its distal end

with a projection extending substantially perpendicularly therefrom through the longitudinal center line of said body, and a flattened second leg pivotally connected at one end to said body at a location substantially diametrically opposite the proximal end of said first leg and having on its other end a projection extending substantially perpendicularly therefrom toward said first leg and underlying the projection on said first leg to releasably hold said legs in spaced apart and substantially parallel relationship to each other when said eye formation is closed, said second leg being swingable away from said first leg to open said eye formation to receive a thread, and the projections on said legs being longitudinally curved so that one extension has a concave inner surface receiving a convex outer surface of the complementary extension to releasably snap the two legs together in eye closing relationship.

3. A needle comprising an elongated body of circular cross sectional shape tapered from a location intermediate its length to both its ends, said body being tapered to a point at one end and having at its other end an eye formation including a flattened first leg extending along and spaced to one side of the longitudinal center line of said body and provided at its distal end with a projection extending substantially perpendicularly therefrom through the longitudinal center line of said body, and a flattened second leg pivotally connected at one end to said body at a location substantially diametrically opposite the proximal end of said first leg and having on its other end a projection extending substantially perpendicularly therefrom toward said first leg and underlying the projection on said first leg to releasably hold said legs in spaced apart and substantially parallel relationship to each other when said eye formation is closed, said second leg being swingable away from said first leg to open said eye formation to receive a thread, said body having a recess therein at the location of maximum diameter opening through the side thereof diametrically opposite the proximal end of said first leg and said second leg having a tongue of partly cylindrical shape received in the recess in said body, said tongue and said body being provided with registering recesses, and a pivot pin extending through said registering recesses pivotally connecting said second leg at said one end thereof to said body.
